REEL

William George Esmond, Cumberland, Md., assignor to Celanese Corporation of America, a corporation of Delaware

Application May 10, 1947, Serial No. 747,287

6 Claims. (Cl. 28—71.7)

This invention relates to apparatus employed in the manufacture of artificial silk filaments, threads, yarn and the like, hereinafter referred to as "yarn," and relates more particularly to a reel adapted to advance helices of yarn in an axial direction. The yarn may be subjected to a treatment with a fluid medium or mediums during the movement of the helices of yarn along the reel.

An object of this invention is the provision of an improved advancing reel characterized by its simplicity and strength of construction.

Another object of this invention is to provide an improved advancing reel embodying a plurality of bars which are angularly spaced with respect to each other, the angular spacing being fixed and equal and which bars are divided into two cages adapted for interdigitating movement.

Other objects of the present invention, together with certain details of construction and combinations of parts, will appear from the following detailed description.

In the drawings wherein a preferred embodiment of this invention is shown,

Fig. 1 is an elevational view of the free end of the advancing reel of my invention,

Fig. 2 is a cross-sectional view along line 2—2 in Fig. 1, and

Fig. 3 is a cross-sectional view along line 3—3 in Fig. 2.

Like reference characters indicate like parts throughout the several views of the drawing.

Referring now to the drawing for a detailed description of my invention, the reel comprises a plurality of spaced, annularly arranged, longitudinally extending bars which are divided into sets, each having an equal number of bars, forming two cages, the bars of which are interdigitated. The bars generally indicated by reference numeral 4 form cage A and the bars generally indicated by reference numeral 5 form cage B. The bars 4 and 5 are supported by means hereinafter set forth, carried by a single shaft 6 fixed in a flange 7 which may be attached to any suitable framework or support (not shown).

Fixed to shaft 6 are cam members generally indicated by reference numerals 8 and 9 being held thereon by set screws 10. Cam members 8 comprises a cam 11 having a circumferential cam surface 12 and an annular cam surface 13 along the edge thereof, and a second cam 14, integral with cam 11, having a circumferential cam surface 15, and an annular cam surface 16. Cam member 9 is constructed similarly to cam member 8 and also comprises two integral cams, cam

17 and cam 18. Cam 17 has a circumferential cam surface 19 and an annular cam surface 21, while cam 18 has a circumferential cam surface 22 and an annular cam surface 23.

The bars 4 of cage A are provided with ears 24 forming brackets in which are journaled pins 25 having mounted thereon cam followers 26 and 27. Cam follower 26 is adapted to be in contact with circumferential cam surface 12 on cam 11, and cam follower 27 is adapted to be in contact with circumferential cam surface 19 on cam 17. The ends of bars 4 are also provided with brackets 28 and 29 in which are journaled cam followers 31 and 32, respectively. Cam follower 31 is adapted to be in contact with annular cam surface 13 on cam 11, and cam follower 32 is adapted to be in contact with cam surface 21 on cam 17. Similarly, the bars 5 of cage B also have two pairs of cam followers. These bars 5 are provided with brackets 33 and 34 in which are journaled cam followers 35 and 36, respectively. Cam follower 35 is adapted to be in contact with the circumferential cam surface 15 of cam 14, and cam follower 36 is adapted to be in contact with circumferential cam surface 22 of cam 18. Bars 5 also have brackets 37 and 38, in which are journaled cam followers 39 and 41, respectively. Cam follower 39 is adapted to be in contact with the annular cam surface 16 of cam 14, and cam follower 41 is adapted to be in contact with annular cam surface 23 of cam 18.

To drive the bars 4 and 5 annularly about shaft 6, there is provided a spider 42 having arms 43, each of which arms carry a ball bearing structure 44 extending into pockets 45 in the bars 4 and 5. The spider 42 is rotatably mounted on a ball bearing structure and a roller bearing structure 47 carried by shaft 6. An internal gear is fixed to spider 42 by means of screw bolts 49. The internal gear 48 is driven by a pinion gear 51 mounted at the end of a shaft 52 passing through flange 7.

Spring 53, attached at one end to loops 54 fixed to spider 42, and at the other end to loops 55 in pockets 56 in bars 4 and 5, are provided to maintain said bars in contact with the circumferential cam surfaces of the cam members 8 and 9.

The motion of the advancing reel of this invention is as follows: As the spider 42 is caused to rotate, the cam followers 26 and 27 running on the circumferential cam surfaces 12 and 19, of cams 11 and 17, respectively, cause the bars 4 of cage A to move in and out. The bars follow a circular path clockwise from point D to point H, then withdraw evenly to point J, the point of

maximum withdrawal, then move outwardly gradually until point D is reached where they are fully extended. At the same time, the rotation of the spider causes the cam followers 35 and 36 on the circumferential cam surfaces 15 and 22 of cams 14 and 18, respectively, to move the bars of cage B in and out. The bars 5 follow a perfectly circular path from point H to point D, then withdraw evenly to point F, the point of maximum withdrawal, then move outwardly gradually to point H where they are fully extended.

With respect to the yarn advancing motion of the bars of the reel, the bars 4 of cage A are caused to advance and retract by the annular cam surfaces 13 and 21 cooperating with cam rollers 31 and 32, respectively. The bars 4 advance evenly from point C to point I and then are retracted to their original position. The bars 5 of cage B are caused to advance and retract by the annular cam surfaces 16 and 23 cooperating with cam followers 39 and 41, respectively. The bars 5 advance evenly from point G to point E and then are retracted to their original position.

The structure of the advancing reel of the present invention presents many advantages. Thus, the spider and cam arrangement permits the axial movement of the bars of the cages to be parallel at all times to shaft 6; the spacing of the bars remains fixed and equal avoiding any abrasion of the yarn; the cam means for effecting interdigitating movement of the cages and the advancing and retracting movement of the bars makes for positive operation thereof and both cages advance uniformly, thus produce perfect helices of yarn.

It is to be understood that the foregoing detailed description is merely given by way of illustration and that many variations may be made therein without departing from the spirit of my invention.

Having described my invention, what I desire to secure by Letters Patent is:

1. A reel for advancing helices of yarn axially, comprising a fixed shaft, a plurality of cams fixed to said shaft, a plurality of longitudinally extending bars for carrying the yarn along the reel, a plurality of rollers on each of said bars for cooperating with said cams, a spider mounted on said shaft for rotation relative thereto for moving said bars around said shaft, a gear attached to said spider and means for rotating said gear, the construction arrangement being such that said cams effect radial and axial reciprocation of said bars as said bars are caused to move around said shaft by said spider.

2. A reel for advancing helices of yarn axially, comprising a fixed shaft, a plurality of cams fixed to said shaft, a plurality of longitudinally extending bars for carrying the yarn along the reel, a plurality of rollers on each of said bars for cooperating with said cams, a spider disposed between said cams and mounted on said shaft for rotation relative thereto for moving said bars around said shaft, a gear attached to said spider and means for rotating said gear, the construction arrangement being such that said cams effect radial and axial reciprocation of said bars as said bars are caused to move around said shaft by said spider.

3. A reel for advancing helices of yarn axially, comprising a fixed shaft, a plurality of cams fixed to said shaft, a plurality of longitudinally extending bars for carrying the yarn along the reel, a plurality of rollers on each of said bars for

cooperating with said cams, a spider mounted on said shaft for rotation relative thereto for moving said bars around said shaft, spring means connected to said spider and said bars for maintaining said rollers on said bars in contact with said cams, a gear attached to said spider and means for rotating said gear, the construction arrangement being such that said cams effect radial and axial reciprocation of said bars as said bars are caused to move around said shaft by said spider.

4. A reel for advancing helices of yarn axially, comprising a fixed shaft, a plurality of cams fixed to said shaft, two cages of longitudinally extending bars wherein the bars of one of said cages are interdigitated with the bars of the other of said cages to form a cylinder of spaced, longitudinally extending bars, for carrying the yarn along the reel, a plurality of rollers on each of said bars for cooperating with said cams, a spider mounted on said shaft for rotation relative thereto for moving said bars around said shaft, a gear attached to said spider and means for rotating said gear, the construction arrangement being such that said cams effect radial and axial reciprocation of said bars as said bars are caused to move around said shaft by said spider.

5. A reel for advancing helices of yarn axially, comprising a fixed shaft, a plurality of cams fixed to said shaft, two cages of longitudinally extending bars wherein the bars of one of said cages are interdigitated with the bars of the other of said cages to form a cylinder of spaced, longitudinally extending bars, for carrying the yarn along the reel, a plurality of rollers on each of said bars for cooperating with said cams, a spider disposed between said cams and mounted on said shaft for rotation relative thereto for moving said bars around said shaft, a gear attached to said spider and means for rotating said gear, the construction arrangement being such that said cams effect radial and axial reciprocation of said bars as said bars are caused to move around said shaft by said spider.

6. A reel for advancing helices of yarn axially, comprising a fixed shaft, a plurality of cams fixed to said shaft, two cages of longitudinally extending bars wherein the bars of one of said cages are interdigitated with the bars of the other of said cages to form a cylinder of spaced, longitudinally extending bars, for carrying the yarn along the reel, a plurality of rollers on each of said bars for cooperating with said cams, a spider mounted on said shaft for rotation relative thereto for moving said bars around said shaft, spring means connected to said spider and said bars for maintaining said rollers on said bars in contact with said cams, a gear attached to said spider and means for rotating said gear, the construction arrangement being such that said cams effect radial and axial reciprocation of said bars as said bars are caused to move around said shaft by said spider.
